[57] CLAIM

The ornamental design for a curtain valance, as shown and described.

DESCRIPTION

FIG. 1 is a front view of a curtain valance showing my new design in the flat state;

FIG. 2 is another front view of the curtain valance of FIG. 1 showing the curtain valance in the gathered state; and,

FIG. 3 is a rear view of the gathered curtain valance of FIG. 2.

The curtain valance which is partially shown for ease of illustration is of indeterminate length. The pattern disclosed repeats uniformly throughout the length of the valance.
